Primary Examiner — Elizabeth J Oswecki

(57) **CLAIM**

The ornamental design for circuit control box, as shown and described.

DESCRIPTION

FIG. 1 is a front, right and top perspective view of a circuit control box showing my new design;

FIG. 2 is a rear, left and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines illustrate portions of the circuit control box that form no part of the claimed design.
